FORK OR SIMILAR ARTICLE

James Russell Price, Esmond, R.I., assignor to Gorham Corporation, Providence, R.I.

Filed Oct. 25, 1966, Ser. No. 4,424

Term of patent 14 years

(Cl. D54—12)

I claim:

The ornamental design for a fork or similar article, as shown.
